TOY GUN

Frederick R. Parker and Lambert P. Moreno, Long Beach,
Calif.; said Moreno assignor to said Parker

Filed Feb. 18, 1963, Ser. No. 73,595

Term of patent 14 years

(Cl. D34—15)

FIGURE 1 is a bottom perspective view of a toy gun,
showing our new design;

FIGURE 2 is a side elevational view;

FIG. 3 is a top plan view;

FIGURE 4 is a rear end view;

FIGURE 5 is a front end view.

The broken line showings of a rotary wing and missile
are for illustrative purposes only.

We claim:

The ornamental design for a toy gun, substantially as
shown and described.
